No. 687,659.

Patented Nov. 26, 1901.

G. A. SCHRIVER.

DISTRIBUTING ROLLER FOR PRINTING PRESSES.

(Application filed Apr. 5, 1901.)

(No Model.)

UNITED STATES PATENT OFFICE.

GEORGE ALBERT SCHRIVER, OF BROOKLYN, NEW YORK, ASSIGNOR OF
ONE-HALF TO ALFRED H. SCHRIVER, OF BROOKLYN, NEW YORK.

DISTRIBUTING-ROLLER FOR PRINTING-PRESSES.

SPECIFICATION forming part of Letters Patent No. 687,659, dated November 26, 1901.

Application filed April 5, 1901. Serial No. 54,456. (No model.)

To all whom it may concern:

Be it known that I, GEORGE ALBERT SCHRIVER, a citizen of the United States, and a resident of the city of New York, borough of Brooklyn, in the county of Kings and State of New York, have invented a new and Improved Distributing-Roller for Printing-Presses, of which the following is a full, clear, and exact description.

10 The object of the invention is to provide certain new and useful improvements in printing-presses to insure a thorough and equal distribution of the ink on the inking-rollers.

15 The invention consists of novel features and parts and combinations of the same, as will be fully described hereinafter and then pointed out in the claims.

20 A practical embodiment of the invention is represented in the accompanying drawings, forming a part of this specification, in which similar characters of reference indicate corresponding parts in all the views.

25 Figure 1 is a front elevation of the improvement as applied. Fig. 2 is a side elevation of the same. Fig. 3 is an enlarged front view of the distributing-roller mounted on a spindle, parts being shown in section. Fig. 4 is a plan view of the bearing for the distributing-roller and its support, and Fig. 5 is an enlarged front elevation of a modified form of 30 the improvement.

Inking-rollers A A' A² of usual construction are journaled in an inking-roller frame B, connected by a link C with an arm D on a 35 rock-shaft E, so that when the printing-press is actuated a reciprocating movement is given to the frame B, and thus the inking-rollers A A' A² are supplied with ink and distribute the same over the type in the usual manner.

40 The peripheral surfaces of the inking-rollers A A' are engaged by the peripheral surface of a distributing-roller F, and a similar roller F' engages the rollers A A' A².

45 Each of the rollers F F' is mounted to turn and to slide lengthwise on a spindle G, having its flattened end G' loosely engaging an elongated slot in a head H' of a bearing H, yieldingly mounted on a support I, fastened by a set-screw J to the inking-roller frame B, 50 as is plainly illustrated in Fig. 2. Each bearing H is pressed on by a spring H², resting with one end on the support I and with its

other end on a pin H³, carried in the bearing H. Thus the spring H² serves to pull on the bearing H and draw the spindle G and the distributing-roller F or F' inward to hold the said distributing-rollers in firm contact with the inking-rollers A A' A². Pins G² are secured in the flattened ends G' of the spindles G inside of the bearings H to hold the spindles against movement in the direction of their length. 55

On the inside of each distributing-roller F F' is formed a nut F², engaging a screw-thread G³ on the corresponding spindle G, so that when the press is in operation and the inking-rollers A A' A² rotate then a corresponding rotary motion is given to the distributing-rollers F F', and by the nuts F² and the threads G³ the said distributing-rollers are moved in the direction of their length, so that a further 60 uniform and equal distribution of the ink on the inking-rollers A A' A² is had. The threads G³ and the nuts F² of the rollers F F' extend in opposite directions, so that when the press is in motion then the distributing-rollers F F' 65 travel in opposite directions to their length to insure a perfect distribution of the ink on the inking-rollers. 70

In one end of each of the distributing-rollers F F' is arranged a spring K, pressing with 80 one end against a collar or flange F³ in the outer end of the corresponding roller, so as to insure a ready return movement of the roller F or F' in case the nuts F² have moved out of engagement with the threads G³ at the 85 time the distributing-roller F or F' has traveled to an extreme outermost position on the corresponding spindle G. The flattened ends of the spindles G' have movement in the heads H' of the spring-pressed bearings to 90 allow the distributing-rollers to readily adjust themselves relatively to the inking-rollers A A' A². 95

The above-mentioned collar or flange F³ besides serving as a stop for the spring K acts 100 also as a journal-bearing, whereby the inking-cylinder is supported upon the spindle G and is properly spaced therefrom. This feature is very important, because as the threads become worn by use the inking-cylinder normally tends to leave its proper position, and should therefore be held in place by some additional part independently of the threads. Moreover, this collar or bearing is easily re-

placed when worn out and saves the more expensive parts from excessive wear. It is lubricated like any other bearing.

The connection between the spindle and its bearing may be differently arranged—for instance, as shown in Fig. 5, by having the flattened end G⁴ of the spindle formed with an elongated slot G⁵, through which extends a bolt L, carried by a support I', fastened to the inking-roller frame B by the set-screw J'.

It is evident from the foregoing that the means for moving the distributing-roller in the direction of its length on the corresponding spindle G are completely out of sight, as they are contained within the distributing-roller, and the means are not liable to get out of order. It will further be seen that by the construction set forth the spindles are held against movement in the direction of their length and cams and like devices heretofore employed for shifting the distributing-rollers bodily with their spindles are entirely dispensed with, and said spindles are free to yield, so as to readily hold the distributing-rollers in proper contact with the inking-rollers. By having the supports I removably connected with the inking-roller frames it is evident that my device can be readily applied to any existing machine or removed therefrom whenever desired.

Having thus fully described my invention, I claim as new and desire to secure by Letters Patent—

1. In a printing-press having inking-rollers, a distributing-roller comprising two concentric members, one fixed and the other free to rotate, and a spring engaging both of said members, as and for the purpose set forth.

2. In a printing-press, a composite distributing-roller comprising a central spindle fixed against rotation, an outer cylinder threaded upon said spindle, a journal-bearing between said spindle and said cylinder, and a spring engaging said spindle and said cylinder.

3. A printing-press having inking-rollers, a distributing-roller in peripheral contact with the inking-rollers, a spindle held against movement in the direction of its length and on which the said distributing-roller is mounted to turn and to slide in the direction of its length, means between the distributing-roller and its spindle, to cause the distributing-

roller to travel in the direction of its length when rotated by said inking-rollers, and bearings held on the inking-roller frame and engaged by the ends of said spindle, said bearings having elongated openings for the flattened ends of the spindle to slide in, as set forth.

4. A printing-press having inking-rollers, a distributing-roller in peripheral contact with the inking-rollers, a spindle held against movement in the direction of its length and on which the said distributing-roller is mounted to turn and to slide in the direction of its length, means between the distributing-roller and its spindle, to cause the distributing-roller to travel in the direction of its length when rotated by said inking-rollers, bearings for the ends of the spindles, supports on the inking-roller frame, and springs pressing the bearings to hold the distributing-roller in firm contact with the inking-rollers, as set forth.

5. In a printing-press having inking-rollers, a composite distributing-roller comprising two concentric members provided respectively with male and female threads, a journal-bearing connecting said members independently of said threads, and a resilient member adapted to hold said concentric members in a position where the said threads will engage each other, substantially as described.

6. A printing-press having inking-rollers, a distributing-roller in peripheral contact with the inking-rollers, a spindle held against movement in the direction of its length and on which the said distributing-roller is mounted to turn and to slide in the direction of its length, and means between the distributing-roller and its spindle, to cause the distributing-roller to travel in the direction of its length when rotated by said inking-rollers, said means comprising a thread on the spindle, a nut on the distributing-roller, and a spring in the distributing-roller, for pressing the latter in the direction of its length, as set forth.

In testimony whereof I have signed my name to this specification in the presence of two subscribing witnesses.

GEORGE ALBERT SCHRIVER.
